CLAIM

The ornamental design for a therapeutic device, as shown and described.

DESCRIPTION

FIG. 1 is a perspective view of the present invention; FIG. 2 is a right side elevational view of the present invention shown in FIG. 1; FIG. 3 is a left side elevational view of the present invention shown in FIG. 1; FIG. 4 is a front elevational view of the present invention shown in FIG. 1; FIG. 5 is a rear elevational view of the present invention shown in FIG. 1; FIG. 6 is a top plan view of the present invention shown in FIG. 1; and, FIG. 7 is a bottom plan view of the present invention shown in FIG. 1.

The broken lines shown in the drawings depict portions of the therapeutic device and form no part of the claimed design.

1 Claim, 6 Drawing Sheets
